CLAIM

I claim the ornamental design for an electric impact driver, as shown and described.

DESCRIPTION

FIG. 1 is a perspective view of an electric impact driver showing my design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

1 Claim, 7 Drawing Sheets
